(57) **CLAIM**

The ornamental design for a medicine portfolio and organizer, as shown and described.

DESCRIPTION

This application is related to the United States application for patent filed concurrently herewith, bearing the title of Medicine Portfolio and Organizer, identified by Ser. No. 13/206, 509, filed under customer number 35856, which application is incorporated herein by reference in its entirety.

FIG. 1 is a perspective view showing the interior of an opened portfolio.

FIG. 2 is a front elevation view of the portfolio shown in FIG. 1.

FIG. 3 is a top plan view of the portfolio shown in FIG. 1.

FIG. 4 is a side elevation view of the portfolio shown in FIG. 1; and,

FIG. 5 is a cross-section view of the portfolio shown in FIG. 1 taken at line 5 in FIG. 3.

The broken lines throughout the drawings form no part of the claimed design.
